(57) **CLAIM**

The ornamental design for a mobile phone as shown and described.

DESCRIPTION

1.1 is a front view of a first embodiment of a mobile phone, showing the new design;

1.2 is a back view thereof;

1.3 is a left view thereof;

1.4 is a right view thereof;

1.5 is a top view thereof;

1.6 is a bottom view thereof;

1.7 is a front perspective view thereof;

1.8 is a rear perspective view thereof;

4.1 is a front view of a second embodiment of a mobile phone, showing the new design;

4.2 is a back view thereof;

4.3 is a left view thereof;

4.4 is a right view thereof;

4.5 is a top view thereof;

4.6 is a bottom view thereof;

4.7 is a front perspective view thereof; and

4.8 is a rear perspective view thereof.

The broken lines in the drawings show portions of the mobile phone that form no part of the claimed design.

1 Claim, 12 Drawing Sheets
